UNITED STATES PATENT OFFICE.

AUGUST W. ULLBERG, OF PHILADELPHIA, PENNSYLVANIA, ASSIGNOR TO THE PHILADELPHIA HARDWARE AND MALLEABLE IRON WORKS, OF PENNSYLVANIA.

DESIGN FOR A FACE-PLATE FOR REGISTERS, &c.

SPECIFICATION forming part of Design No. 30,569, dated April 18, 1899.

Application filed March 18, 1899. Serial No. 709,690. Term of patent 14 years.

To all whom it may concern:

Be it known that I, AUGUST W. ULLBERG, a subject of the King of Sweden and Norway, residing in the city and county of Philadelphia, State of Pennsylvania, have invented and produced a new and original Design for a Face-Plate of a Register, Ventilator, or Similar Class, of which the following is a specification, reference being had to the accompanying drawings, forming part thereof.

The leading features of my design for a face-plate, more particularly that of a register or ventilator, are, first, a central medallion of concentric circular figures, and, next, a field of rectangular panels of scroll-shaped figures.

Figure 1 represents a face view of a face-plate embodying my design. Fig. 2 represents a section thereof on line *x x*, Fig. 1.

In the drawings, A designates a face-plate at the center of which is the medallion B,

consisting of the concentric circular figures C and D, the figure C being formed of the ring E, with radiating points F, and quatrefoils G joining said points. The figure D is formed of festooned scrolls H and alternating trefoils J. Surrounding the medallion is the field, consisting of side panels K, formed of rectangular frames with scrolls L, somewhat heart-shaped, therein. At the corners of the field are panels M, with pointed figures N therein.

Having thus described my invention, what I claim as new, and desire to secure by Letters Patent, is—

The design for a face-plate substantially as shown and described.

AUGUST W. ULLBERG.
